Paul D. Wright
ATTORNEY.

UNITED STATES PATENT OFFICE.

ORION ESMOND JOHNSON, OF WATERLOO, IOWA.

MITER BOX.

Application filed January 4, 1922. Serial No. 526,945.

To all whom it may concern:

Be it known that I, ORION ESMOND JOHNSON, a citizen of the United States, residing at Waterloo, in the county of Black Hawk 5 and State of Iowa, have invented certain new and useful Improvements in Miter Boxes, of which the following is a specification, reference being had therein to the accompanying drawing.

10 This invention relates to certain new and useful improvements in miter boxes, the object being to provide a miter box with saw guides which are capable of swinging in vertical and horizontal planes in order to allow the box to be used for cutting the material for forming various kinds of joints and angles.

15 Another and further object of the invention is to provide novel means for locking 20 the saw guides in adjusted position.

A still further object of the invention is to provide a miter box which is exceedingly simple and cheap in construction, the parts being so arranged and connected together 25 that a very strong and durable box is formed, the saw guides being so mounted that they will be rigidly locked in adjusted position so that a true cut can be made.

Other and further objects and advantages of the invention will be hereinafter set forth and the novel features thereof defined by the appended claims.

In the drawings,

Figure 1 is a top plan view;
35 Figure 2 is a front elevation, partly in section;

Figure 3 is a section taken on line 3—3 of Figure 1; and

40 Figure 4 is a section taken on line 4—4 of Figure 1.

In the embodiment of my invention as herein shown 1 indicates a bed plate mounted on legs with a reduced central portion cut to form a substantially tri-angular guide 45 way and to provide a segmental rack 2 for the purpose hereinafter fully described.

Secured to the bed plate are back plates 3, the inner edges of which are cut off obliquely and terminate at the inner edge of the tri- 50 angular guide way as clearly shown in Figures 1 and 4.

Pivottally mounted on the bed plate centrally of the same at the rear edge within the reduced portion is a lever 4 herein shown 55 mounted on a bolt 5, said lever having reduced ends 6 forming pivots for tubular saw

guides 7 which are connected together by a grooved bar 8 as clearly shown in Figure 3. The saw guides are secured in position on the pivots 6 by swedging the ends thereon as 60 clearly shown and it will be seen that by this construction the lever 4 is capable of swinging in a horizontal plane and the saw guides in a vertical plane and as the guides are connected together by the bar 8, they are 65 held in true alignment. The tubular guides are slotted to form guide ways for the saw.

Secured on the lever 4 within the cut away portion of the bed is a block 9 carrying a grooved strip 10 which is arranged in such 70 a manner that it can be removed and a new block inserted when the same has been cut up by the saw when the box is in use, this strip protecting the bottom of the box and while I have shown it secured in position in 75 this particular manner, it is, of course, understood that it can be secured in various ways. The pivot 5 also secures this block in position and in use the securing bolts are preferably countersunk.

80 The underside of the lever is grooved as shown at 11 and secured within the groove is an arm 12 carrying a detent 13 which extends through a slot formed in the top of the lever and is adapted to engage the rack 2 so 85 as to hold the lever in its adjusted position. The arm 12 with the detent is held into engagement with the rack by a spring 14 mounted on a push pin 15 which extends through an opening in the lever and has its 90 lower end connected to the arm 12 as shown in Figure 3 so that when it is desired to shift the lever with the saw guides, the push pin is forced downwardly which moves the detent out of engagement with the rack 95 in order to allow the lever to be swung in a horizontal plane.

When the push pin is released, the detent is raised upwardly so as to seat itself between the teeth of the rack in order to lock 100 it securely. The forward end of the lever carries a rack 16 adapted to be engaged by a spring detent 17 carried by the front saw guide. The spring detent as herein shown comprises a shank portion 18 having a head 105 at its outer end, the shank being secured by a coil spring 19 so that the detent is normally held into engagement with the rack and when it is desired to shift the guides into different vertical planes, the shank is 110 pushed inwardly so as to disengage the detent from the rack and the saw guides are

free to swing on the pivot 6 so that when the detent is released, the guides will be locked in their adjusted position.

While I have shown certain details of construction, I am aware that these can be changed without departing from my invention and therefore I do not wish to limit myself to the exact construction as herein shown as my invention consists in providing 10 a miter box with a pivoted lever on the ends of which are pivotally mounted saw guides.

What I claim is:—

- 15 1. In a miter box, the combination with a bed plate, of a lever pivotally mounted on the underside of said plate having pivots at its end, saw guides pivotally mounted on said pivots connected together by a bar and means for locking said saw guides in their adjusted position.
- 20 2. A miter box comprising a bed plate having a reduced portion forming a guide way, a lever pivotally mounted under said bed plate carrying a strip working in said guide way, said lever having pivots at its ends, saw guides mounted on said pivots connected together by a bar, means for locking said lever in adjusted position and means for locking said saw guides in their adjusted position upon said pivots.
- 25 3. A miter box comprising a bed plate having a cut out portion to provide a segmental rack, a lever pivotally mounted on the under side of said bed plate having a spring detent adapted to engage said rack, said lever being provided with reduced ends forming pivots, saw guides pivotally mounted upon said pivots, a bar connecting said

saw guides, a rack carried by said lever and a detent carried by one of said saw guides adapted to engage said rack.

40

4. A miter box comprising a bed plate having a pivoted lever provided with reduced ends, tubular saw guides pivotally mounted on the ends of said lever, a bar connecting said saw guides, said lever being 45 provided with a groove in its under face having a slot extending through the top wall thereof, a rack formed on said bed plate, an arm mounted in the groove of said lever carrying a detent adapted to engage said 50 rack, a push pin mounted on said lever connected to said arm, a spring surrounding said push pin for holding said detent in engagement with said rack and means for locking said pivotally mounted saw guides 55 on said lever in adjusted position.

5. A miter box comprising a bed plate mounted on legs having a cut out portion to produce a segmental rack, a lever mounted on the under side of said bed plate having a block working in said cut out portion, an interchangeable strip carried by said block working in said guide way, said lever having reduced ends to form pivots, tubular saw guides mounted upon the ends of said lever, 65 a detent carried by said lever for engaging said rack, a rack formed on one end of said lever and a spring detent carried by one of said saw guides adapted to engage said rack for locking said saw guides in adjusted 70 position.

In testimony whereof I hereunto affix my signature.

ORION ESMOND JOHNSON.
